UNITED STATES PATENT OFFICE.

EDWARD J. DEEGAN, OF NEW YORK, N. Y.

AUTOMATIC ASH-SIFTER.

No. 908,970.

Specification of Letters Patent.

Patented Jan. 5, 1909.

Application filed February 29, 1908. Serial No. 416,480.

To all whom it may concern:

Be it known that I, EDWARD JOSEPH DEEGAN, a citizen of the United States, and a resident of the city of New York, borough of Manhattan, in the county and State of New York, have invented a new and Improved Automatic Ash-Sifter, of which the following is a full, clear, and exact description.

10 My invention relates to sifters for loose materials, such as ashes, my more particular object being to prevent the formation of excessive dust during the sifting process, and also to effectively separate the coarser materials from the fine dust.

More particularly stated, my invention is an ash sifter of simple and convenient form, wherein the nuisance due to flying ash dust is abated as far as practicable, and in which 20 a large proportion of coal and cinders remaining in the ash is extracted by the automatic action of the device.

Reference is to be had to the accompanying drawings forming a part of this specification, in which similar characters of reference indicate corresponding parts in both the figures.

Figure 1 is a perspective showing my improved ash sifter mounted upon the top of an ash-can and ready for action, this view showing the hopper into which the ashes are poured at the start, and also showing the swinging door at the bottom, whereby the coal cinders, clinkers and other larger portions of material are ejected automatically; and Fig. 2 is an enlarged central section through the ash-sifter showing the chutes for fine ashes and coarser materials and the various doors, screens and baffles.

30 An ash-can top is shown at 3 and is provided with a removable door 3^a. Resting upon the top 3 is a box frame having an inclined portion 4 and a short vertical portion 5. Mounted within the portion 5 is a hopper 6 provided at its bottom with an opening 7. Disposed below this opening and mounted rigidly within the portion 5 is a plate 8, inclined obliquely downward to the proximate center of the portion 5. A swinging door 9 is mounted upon the hopper 6, and is normally pressed against the plate 8 by aid of a spring 9^a. At 10 is a screen mounted within the inclined portion 4. A baffle-plate 11 is connected with the lower end of the screen 10 and inclines slightly backward under the screen 10, or to the left, according to Fig. 2.

Another screen 12 is disposed parallel with the screen 10, but in a plane slightly lower than that of this screen. The screen 12 is supported upon a rod 13 extending directly 60 across the box frame and engaging the baffle-plate 11.

Mounted upon a stationary wall 14 is a baffle plate 15 inclined inward or to the left, according to Fig. 2. A door 16 is mounted 65 upon the wall 14 and is adapted to swing outwardly, as will be understood from Fig. 2. This door is normally held by its own weight against a wall 17 which supports the lower end of the screen 12.

70 At 18 is a baffle plate mounted upon the top 3, this top being provided with an opening 20 into which the plate 18 projects, as will be understood from Fig. 2. The box frame is supported by a brace 19 connected 75 rigidly with it.

The operation of my device is as follows: The doors 9 and 16 being normally closed, as above described, the ashes are poured into the hopper 6. They pass through the opening 7 and fall upon the inclined plate 8 which directs them to the left. The door 9 is opened by the weight of the materials, and the latter are thence poured upon the screen 10, striking the same at a very abrupt angle. 80 The fine ashes pass through the screen 10 and are guided obliquely downward through the opening 20 into the ash can. The coarser materials, such as cinders and unburned coal, roll down the screen 10 and bounce onto the 90 screen 12, shaking the latter. Any fine ashes which may rest upon this screen are thus shaken through and pass into the opening 20. Some of the finer ashes passing through the screen 10 follow this screen downwardly to its 95 lower end, and then, passing through, strike the plate 11, being thus deflected to the left and prevented from reaching the screen 12. Any material striking the baffle plate 15 is projected to the left and made to strike the 100 screen 12 so as to sift the finer materials through the latter. Finally any material striking the plate 18 is baffled toward the left. The coarser materials, piece by piece, strike the door 16 and open it, and this door, 105 being closed by its own weight, prevents, as far as practicable, the escape of fine ashes and dust into the outer atmosphere. The door 9 acts to some extent in the same manner, in that it prevents upward travel or retrogression of any loose or fine material tending to contaminate the air. Every chance,

however, is afforded for the removal of the coarser materials which, as experience has shown, have more or less value as fuel.

Having thus described my invention, I claim as new and desire to secure by Letters Patent:

In an ash sifter, the combination of a box frame provided with a vertically disposed portion and with an inclined portion, a hopper mounted upon said vertically disposed portion, a plate disposed within said vertically disposed portion and extending approximately from the edge of said vertically disposed portion, a swinging door mounted upon said hopper, a spring connected with said hopper and with said swinging door for normally forcing said swinging door into engagement with said plate, a pair of screens

disposed within said inclined portion of said box frame, said screens being in different planes, the lower end of one screen being above the upper end of another screen, a plate connecting said screens together and lying in a plane differing from that of the screens, and a brace connected with said inclined portion of said box frame for supporting the same so as to give a proper inclination to said screens.

In testimony whereof I have signed my name to this specification in the presence of two subscribing witnesses.

EDWARD J. DEEGAN.
